EUGÉNE RONCERAY, OF PARIS, FRANCE, ASSIGNOR TO SOCIETE ANONYME DES ETABLISSEMENTS PH. BONVILLAIN & E. RONCERAY, OF PARIS, FRANCE, A CORPORATION OF FRANCE.

MOLDING-MACHINE.

1,091,020.

Specification of Letters Patent. Patented Mar. 24, 1914.

Application filed June 20, 1913. Serial No. 774,785.

To all whom it may concern:

Be it known that I, EUGÉNE RONCERAY, a citizen of France, residing at Paris, France, have invented certain new and useful Im- 5 provements in Molding-Machines, of which the following is a specification.

This invention has reference to molding machines, and particularly to machines for simultaneously ramming the halves of a sand mold. It has for its primary objects the provision of improved apparatus for simultaneously ramming the halves of sand molds; the provision in apparatus of the character described of improved means for 10 removing the sand molds from the flasks; and in general the provision of improved apparatus, simple in construction and effective in operation, for ramming the halves of the molds and removing the completed sand 15 molds from the flasks. My invention further contemplates the provision of improved means for automatically locking the flasks together and the provision of improved means for protecting the working 20 parts from sand. Still another object of the invention resides in the provision of a novel means for supplying fluid pressure to the operating pistons and in the provision of novel means for supporting the flasks 25 in the machines.

The foregoing together with such other objects as may hereinafter appear or are incident to the invention, I accomplish by means of mechanism which I have shown in 30 the accompanying drawings in preferred form. In the drawings:

Fig. 1 is a sectional elevation of my improved apparatus; Fig. 2 is a side elevation of Fig. 1 partially in section; Fig. 3 is a 35 plan view of the apparatus in inoperative condition; Fig. 4 is a partial section and side elevation of the flask; and Fig. 5 is a plan view of the upper flask.

In carrying out my invention I provide a 40 main frame work 1 provided at one side with a vertically disposed collar 2 in which is keyed a vertical supporting column 3. Rotatably mounted in the upper portion of the column 3 is a cross bar 4 provided with a fixed 45 platen 5. Arranged on the main frame work 1 on the side opposite the collar or socket 2, is a standard 8^a in which is detachably mounted a vertically extending rod 8 on which is pivoted a hooked rod 7 50 adapted to engage the projection 6 formed

on the cross bar 4. Intermediate the socket 2 and the cross bar 4, the column 3 is provided with a fixed abutment 4^a. A sleeve 4^b is mounted on the column 3 and bears at its lower end against the abutment 4^a, said 60 sleeve serving to position the cross bar 4 on the column but permitting free rotation thereof about the column. Slidably mounted on the sleeve 4^b between the fixed abutment 4^a and the cross bar 4 is a socket or collar 65 11 carrying a forked frame 9 which is provided with three notched lugs 14. The lugs 14 are adapted to be engaged by pins 13 mounted on the pattern plate 10, the arrangement of the forked frame and supports being such as to provide a three-point 70 support for the pattern plate.

Located beneath the main frame is a cylinder 17 which is rigidly secured to the frame work by means of the stay rods 18. 75 A hollow piston 19 is mounted in the cylinder 17 and is closed at its upper end by a plate 21 in which are mounted four rods or posts 22. Fastened to the upper end of the posts 22 is a plate 23 on which a false bottom 31 for the flasks is adapted to rest. Mounted within the hollow piston 19 is a piston 20 into which is threaded a vertical 80 rod 27 which passes through the frame work 1 and is guided by the bearing block 28 fastened to the frame work 1. The upper part of the rod 27 is provided with an enlargement or shoulder 26 provided with an interiorly threaded aperture, with which the threaded stem 25 of the plate 24 has engagement. The plate 24 is provided with external threads or corrugations 24^a, the purpose of which will hereinafter appear. 85

A frame work 29 is carried on the shoulder 26, (see particularly Figs. 1 and 2), and this frame work detachably carries the lower or drag flask 30 of the mold. The upper flask or cope 32 is normally carried on the pattern plate 10. The flask 32 is provided with projections 33 arranged on opposite 100 sides.

The cross bar 4 is provided on opposite sides with blocks 38 in which are mounted axles 37 having at their outer ends the sleeves 36 adapted to receive the axles 35 of the lever 105 arms 34. By the arrangement of axles substantially at right angles to one another rotative movement may be imparted to the arms 34 about a vertical axis and about a substantially horizontal axis. The construc- 110

- tion is clearly shown in Fig. 3 a portion of which is broken away to illustrate the mounting of the axis. As shown in Fig 1 the arms 34 are bent on themselves to provide a crook adapted to embrace the projections 33. The arms are normally held in the position indicated in Figs. 1 and 2 by the springs 16 which tend to hold the arms inward toward the platen 5.
- 10 The piston 19 is preferably operated hydraulically, liquid under pressure being admitted into the lower portion of the piston 17 through the connection 15. A volume of air is imprisoned in the hollow piston 19 by the piston 20, and liquid under pressure is admitted to the chamber in the piston 19 above the piston 20 by means of the port 48 and the pipe 49 which is supported from the cylinder 17 and mounted in such manner that the piston 19 can freely rise in the cylinder 17. This is accomplished by providing a sleeve 50 mounted on the head of the piston 19 and into which the pipe 49 telescopes. Leakage is prevented by the stuffing box 51.
- 15 The flask 32 is provided with a pair of diagonally disposed downwardly projecting pins 40 mounted in lugs 42, the upper faces of which are inclined to shed off any sand that may fall down. These pins engage apertured lugs 41 formed on the lower flask 30. The lower flask is provided with a pair of hooks 43 adapted to be engaged by the hooked arms 44 pivotally mounted on the lugs 46 formed on the upper flask. A plate 47 preferably composed of rubber or leather is secured to the flask 32 above each of the arms 44. These plates are adapted to prevent sand from working in to the hooks on the arms 44 and the points of pivotal support therefor. In order to prevent sand from working into the bearing block 28, a collapsible sheathing 45 extends between the shoulder 26 on the rod 27 and the block 28.
- 20 The operation of the apparatus is as follows: The swinging arm 7 is swung clear of the catch 6 and the cross bar 4 is rotated about the column 3 clear of the machine. The forked frame 9 carrying the pattern plate 10 and the flask 32 is also swung to one side, the position of the cross bar and of the frame 9 being illustrated in Fig. 3. The flask 30 is in the position shown in Figs. 1, 2, and 3. Both flasks are now filled with sand, the forked frame 9 is swung about the column 3 until the pattern plate is in alignment with the flask 30, and the cross bar 4 is swung about until the platen 5 is in vertical alignment with the flasks. The arm 7 is then hooked over the catch 6 and pressure is admitted into the lower part of the cylinder 17, causing the piston 19 to rise. As the piston rises, it will be clear that the rods 22 elevate the plate 23 and the false bottom 31 of the flask 30. The piston 20 rises with

the piston 19 because of air imprisoned in the lower part of the chamber of the piston 19, and as the piston 20 rises, the rod 27, frame work 29, and flask 30 are also elevated. It will thus be seen that the plate 23 and false bottom 31 and the flask 30 rise together.

As the upward movement of the parts continues, the flask 30 comes into engagement with the bottom of the pattern plate 10, and the latter is elevated lifting with it the flask 32 until the sand in the latter comes into engagement with the fixed platen 5. The sand in both flasks is rammed simultaneously by the compressive action of the rising piston 19. The arms 34 are now moved outwardly and downwardly so as to engage the projections 33 on the under sides thereof, the springs 16 serving to hold the arms in secure engagement with the projections.

The pressure is then exhausted from beneath the piston 19, and the piston 19 and the piston 20 descend by reason of the weight which they carry. The downward movement of the parts brings the pattern plate 10 into engagement with the frame 9, and the movement of the pattern plate is arrested, while the downward movement of the flask 30 and false bottom 31 continues until the parts are in substantially the position shown in Fig. 1. The frame 9 carrying the pattern plate 10 is swung out of the way. The downward movement of the parts just described effects the drawing of the pattern and pattern plate from both the upper and the lower flasks.

Pressure is again admitted to the under side of the piston 19 causing the flask 30 and bottom 31 to rise again until the flask 30 comes into engagement with the flask 32, now supported by the arms 34. As the flasks come together the hooked arms 44 automatically engage the hooks 43 on the flask 30, and the two flasks are locked together. The arms 34 are then actuated to release the projections 33, and the pressure is again exhausted from the under side of the piston 19 while at the same time liquid under pressure is admitted through the pipe 49 to the upper side of the piston 20. The piston 19 descends by reason of the weight it carries, as does the piston 20, the latter being also driven down by the pressure on the upper side thereof, such pressure serving to compress the volume of air confined in the hollow piston 19. It will be seen from the foregoing, that during this movement the piston 20 and rod 27 descend more rapidly than the piston 19 and the false bottom 31. The piston 20 and rod 27 carry the flask 30 and flask 32 downwardly more rapidly than the false bottom 31 descends, and as a result the sand in both flasks is partially forced out of the flasks.

The downward movement of the rod 27

continues until the shoulder 26 engages the block 28, after which the pressure above the piston 20 acts on the plate 21 and causes the piston 19 to ascend, this movement taking place because the downward movement of the rod 27 and piston 20 is limited by the block 28. The elevation of the piston 19 forces the sand molds and the false bottom 31 completely out of both flasks, and the 10 false bottom is then picked up together with the sand molds and carried to the foundry. Pressure is exhausted from the upper side of the piston 20, the parts assume their normal position, and the apparatus is ready for 15 another operation. It will, of course, be understood that the apparatus is suitably vibrated by any preferred vibratory mechanism 52 when the pattern plate is being drawn from the flasks.

Referring to the plate 24 and the threaded stem 25, it will be seen that the said plate takes against the under side of the plate 23, and that by varying the elevation of the plate 24 with respect to the rod 27, the relative position of the piston 20 in the piston 19 can be changed. This effects a similar change in elevation of the flask 30 with respect to the plate 23 and false bottom 31. The flask 30 and false bottom 31 can therefore be adjusted in relative elevation to accommodate any desired quantity of sand. The adjustment of the plate 24 is facilitated by reason of the external teeth 24^a on said plate.

The apparatus is simple and effective in operation. A large saving of time and labor is effected, not only with respect to the ramming of the flasks but also with respect to the subsequent operations in which the molds 40 are removed from the flasks. Another advantage of the apparatus resides in the fact that the same flasks can be used in making a large number of molds, thereby reducing the quantity of the equipment necessary in 45 carrying out normal molding operations. It will also be clear that the apparatus can be readily accommodated for making molds of different sizes by changing the parts.

The machine rams the flasks and there- 50 after ejects them, and it will be seen that the sand molds are ejected one after the other out through the top flask which is advantageous since the sand of both parts of the mold is supported during the ejecting 55 operation. The same apparatus that effects the ramming of the molds also effects the ejection of the completed molds.

What I claim is:

1. In molding apparatus the combination 60 of a ramming member, a cylinder, a hollow piston therein, a second piston in the hollow piston, a flask carried on one of the pistons, a false bottom carried by the other, means for admitting fluid pressure to advance the 65 pistons substantially simultaneously to the

ramming member to ram the sand, and means for admitting fluid pressure into the hollow piston above the second piston whereby said pistons move relatively to each other.

2. In molding apparatus the combination 70 of a ramming member, a cylinder, a hollow piston therein, a second piston in the hollow piston, a flask carried on one of the pistons, a false bottom carried by the other, means for admitting fluid pressure in the 75 lower portion of the cylinder to raise both pistons to the ramming member to ram the sand in the flask, means for admitting fluid pressure into the hollow piston above the second piston, whereby the two pistons move 80 relatively with respect to one another.

3. In molding apparatus the combination 85 of a ramming member, a cylinder, a hollow piston mounted in the cylinder, a second piston mounted in the hollow piston, there being a cushion of air beneath the bottom of the second piston, a flask mounted on one of the pistons, a false bottom on the other, means for admitting fluid pressure into the cylinder to raise the pistons toward the ramming member, and means for admitting fluid pressure into the hollow piston above 90 the second piston.

4. In molding apparatus the combination 95 of a frame, a ramming member, a cylinder on the frame, a hollow piston in the cylinder, a second piston in the first piston, a flask carried by one of said pistons, a false bottom carried by the other piston, means for admitting fluid pressure into the cylinder 100 to elevate the pistons toward the ramming member, means for admitting fluid pressure into the hollow piston above the second piston, and means for limiting the downward movement of the second piston. 105

5. In molding apparatus the combination 110 of a ramming block, a hollow movable member, a piston member in said hollow member, a flask carried by one of said members, a false bottom carried by the other, means for elevating the movable member toward the ramming block, and means for admitting fluid pressure into the hollow member above the piston member whereby said members are moved relative to each other.

6. In molding apparatus the combination 115 of a frame, a ramming block thereon, a flask, means for elevating the flask toward the block, engaging means on the flask, and means adjacent the block adapted to receive 120 the engaging means on the flask comprising members mounted for double rocking movement away from and transverse of the frame.

7. In molding apparatus the combination 125 of a frame, a ramming block thereon, a flask, means for elevating the flask toward the block, engaging means on the flask, means adjacent the block adapted to receive 130 the engaging means on the flask comprising

members for double rocking movement away from and transverse of the frame, and spring means for holding said means in engagement with the flask.

5. 8. In molding apparatus the combination of a ramming member, a flask, a false bottom therefor, a means for supporting the flask, a means for supporting the false bottom, both of said means being adapted to advance the flask and bottom to the ramming member to ram the sand, and means whereby the relative elevation of the flask and bottom can be varied.
10. 9. In molding apparatus the combination of a ramming member, a flask, a false bottom therefor, a means for supporting the flask, a means for supporting the bottom, and a means for variably supporting the flask on its supporting means with respect to the bottom, both of said first two means being adapted to advance the flask and the bottom toward the ramming member.
15. 10. In molding apparatus the combination of a ramming member, a flask, a false bottom therefor, a hollow piston carrying
20. 25. to the bottom, both of said first two means being adapted to advance the flask and the bottom toward the ramming member.

the false bottom, a second piston mounted in the first, means for elevating the pistons to advance the flask and bottom, and means for admitting fluid pressure into the hollow piston above the second piston whereby said 30 pistons are moved relatively to each other.

11. In molding apparatus the combination of a frame, a ramming member, a cylinder carried by said frame, a hollow piston mounted in the cylinder, a plate on said 35 piston, a second piston mounted in the first piston, a flask carried by the second piston, a variable abutment on the second piston adapted to bear against the plate and adjust the position of the second piston relative to the first, and means for advancing the pistons.

In testimony whereof I have hereunto signed my name in the presence of the two subscribed witnesses.

EUGÉNE RONCERAY.
